LLC; Clifford D. Hyra(57) **CLAIM**

The ornamental design for a drying machine, as shown and described.

DESCRIPTION

FIG. 1 is a perspective view of the drying machine, showing the front and left sides thereof.

FIG. 2 is a perspective view thereof, showing the front and right sides.

FIG. 3 is a perspective view thereof, showing the rear and left sides.

FIG. 4 is a perspective view thereof, showing the rear and right sides.

FIG. 5 is a rear view thereof.

FIG. 6 is a front view thereof.

FIG. 7 is a right side view thereof.

FIG. 8 is a left side view thereof.

FIG. 9 is a perspective view thereof, showing the top, front and right sides.

FIG. 10 is a perspective view thereof, showing the top, front and left sides; and,

FIG. 11 is a perspective view thereof, showing the bottom, front and left sides.

The broken lines are showing portions of the drying machine that form no part of the claimed design.
